CARTON

William Kenneth Clark, Chicago, Ill., assignor to
 Industrial Patents Corporation, Chicago, Ill.,
 a corporation of Delaware

Application May 27, 1935, Serial No. 23,543

3 Claims. (Cl. 229—36)

This invention relates to improvements in boxes or cartons formed from a single blank of cardboard or other suitable material in which flaps, integral with the bottom and side walls thereof, 5 and adapted to be interfolded and interlocked, are provided to form the end walls.

One of the objects of this invention resides in the novel shape and position of the end flaps extending from the bottom and side walls which permits a substantial saving of material in cutting the blanks from a continuous sheet.

Another object of this invention resides in the novel features of the end flaps forming a part of the box or carton blank which permits the 15 box or carton to be quickly assembled and securely held in shape.

Other objects of the invention will be apparent from the description and claims which follow.

Figure 1 of the drawings is a plan view of blanks from which the carton of the present invention may be formed and illustrates the relation of the end flaps of adjacent blanks as they are cut from a continuous sheet of material.

Figure 2 is a perspective view of a carton formed from one of the blanks shown in Figure 1.

The carton illustrated in Figure 1 is formed from a single blank of cardboard or other suitable material scored and cut as shown in Figure 1, and comprises a bottom 1, side walls 2 and 3, top 4, and ends 5, said ends being formed from a plurality of interfolding and interlocking flaps integral with said bottom and side walls, comprising flaps 8 and 9 extending from bottom 1, flaps 6 and 7 extending from side wall 2, and flaps 10 and 11 extending from side wall 3. Flaps 12 and 13, adapted to be folded inwardly at the top, are integral with and extend from the upper lateral edges of end flaps 10 and 11, respectively. Top 4 is provided with tongue 14 having rounded 40 outer corners 15, which tongue extends the full length of and is integral with top 4 at its outer edge.

In the formation of the box, flaps 8 and 9 are folded at right-angles to bottom 1. Flaps 8 and 9 are shorter than the adjacent end flaps and if desired, may be slightly converged at their lateral edges 16 to facilitate folding of the adjacent end flaps.

Flaps 10 and 11 are cut away to provide tongue 50 portions 17 adapted to fit and interlock within slits 18 in the flaps 6 and 7 to secure the ends 5. Tongues 17 are formed by cutting a downwardly extending angular slot 19 at the upper outer edge of flaps 10 and 11, having a narrowed throat 20, and by cutting said flaps from their outer edges

on a curved line indicated by numeral 21, which line, it will be noted, swings downwardly and then upwardly and terminates on a line substantially horizontal with throat 20. Flaps 10 and 11 are cut away as indicated by line 22, said line commencing slightly below the terminus of line 21 and extending obliquely to the lower corner adjacent side wall 3.

Designations of position such as the terms "upper" and "lower" as used in this specification will be understood to denote portions of the respective parts as they appear in the formed carton shown in Figure 2 or on the blanks shown in Figure 1 and will be clear from the context.

Slits 18 are preferably constructed by cutting flaps 6 and 7 diagonally as indicated by line 23 commencing near the upper corner adjacent side wall 2 and extending downwardly and outwardly a distance sufficient to accommodate the insertion of tongue 17. To facilitate the insertion of tongue 17, cut 23 continues on a sharp turn outwardly and backwardly on line 24 for a short distance parallel to line 23, whence it continues outwardly and upwardly in a broad arc 25, terminating on a line substantially horizontal to its commencement.

The saving of material to which reference has been made is accomplished by the novel shape and position of the parts, the flaps of adjacent blanks being cut from a continuous sheet in interfitting relationship as shown in Figure 1. End flaps 8 and 9 are of shorter extension than their adjacent flaps and flaps 10 and 11 are cut obliquely at their lower outer corners. Flaps 6 and 7 are cut obliquely at their lower outer corners as indicated by line 26, commencing at the approximate center of the outer edge and extending inwardly and downwardly to the lower lateral edge in line with the outer edge of end flaps 8 and 9. Top flaps 12 and 13 are cut obliquely at their upper outer corners as indicated by line 27, commencing at the approximate center of the outer edge thereof and continuing downwardly and outwardly to the approximate center of the outer lateral edge. Top flaps 12 and 13, if desired, may be cut away at their upper inner corners as indicated by line 28 equal to line 27 to add symmetry and attractiveness thereto.

It will be seen by reference to Figure 1 that by reversing the blanks at their lateral edges, the several flaps of one blank will interfit with the flaps of the adjacent blank, and that as the same are cut from a continuous sheet, a strip of material, as indicated between lines A and B, will be saved for each two blanks cut.

- The proposed carton is assembled by folding end flaps 8 and 9 and side walls 2 and 3 upwardly at right-angle to bottom 1. Flaps 6 and 7 are folded inwardly against flaps 8 and 9, respectively. Flaps 10 and 11 are folded inwardly against flaps 6 and 7, respectively, the tongue portions 17 of the flaps 10 and 11 being inserted through cut 23 of slit 18, by which throat 20 will become hooked at cut 23 and secure the ends 10 5 in locked formation. Flaps 12 and 13 are then folded inwardly and top 4 is folded over on flaps 12 and 13, the top 4 being secured by inserting tongue 14 between side wall 2 and the product contained in the carton.
- 15 The term "cardboard" as herein used will be understood to include any flexible material adapted for the manufacture of containers, such as strawboard, paper board, pulpboard, and the like, whether or not they have been treated with 20 wax or other grease-proof or moisture-proof composition.

I claim:

1. A carton blank comprising a bottom and two side walls each provided with an end flap extending therefrom, the flap extending from one side wall being cut to form a tongue portion on the outer edge thereof, and being provided with a top flap extending from the upper lateral edge obliquely cut at its upper outer corner, the flap 25 extending from the opposite side wall being provided with a diagonal slit for the reception of said tongue portion and being cut obliquely at its lower outer corner, the flap extending from the bottom being shorter than the adjacent side 30

flaps, the portions cut away by obliquely cutting the top flap and the slitted end flap and the shortened bottom flap permitting the flaps of adjacent blanks to be cut from a continuous sheet in interfitting relationship.

2. A carton blank comprising bottom and side walls, each provided with a flap extending therefrom, the lower outer corner of the flap extending from one side wall being cut away to form a tongue portion on the outer edge thereof, the flap extending from the opposite side wall being provided with a slit for the reception of said tongue portion, the flap extending from the bottom being of a shorter extension in relation to adjacent flaps, the portion cut from said tongue flap and the shortened extension of said bottom flap permitting flaps of adjacent blanks to be cut from a continuous sheet in interfitting relationship.

3. A carton blank comprising bottom and side walls, each provided with a flap extending therefrom, the flap extending from one side wall being cut away to form a tongue portion on the outer edge thereof, said last-mentioned flap being provided with a top flap extending from its upper 25 lateral edge, the flap extending from the bottom being of a shorter extension in relation to adjacent flaps, the portion cut from said tongue flap and the shortened extension of said bottom flap permitting flaps of adjacent blanks to be cut 30 from a continuous sheet in interfitting relationship.

WILLIAM KENNETH CLARK.
